(57) **CLAIM**

I claim, the ornamental design for a multi-purpose two-way heating cooker, as shown and described.

DESCRIPTION

FIG. 1 is a top and front perspective view of a multi-purpose two-way heating cooker, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a reference perspective view showing how two infrared lamps of the multi-purpose two-way heating cooker are moved and fixed to a lower side of a cooking pan; and, FIG. 9 is a reference top plan view showing how the two infrared lamps are moved and fixed to the lower side of the cooking pan.

The broken lines shown in the figures are for illustrative purposes only and form no part of the claimed design.
